CLAIM

The ornamental design for rom chip attachment of an ink bottle, thereof as shown and described.

DESCRIPTION

FIG. 1 is a front, top, and right side perspective view of a rom chip attachment of an ink bottle showing our new design;

FIG. 2 is an enlarged perspective view of FIG. 1;

FIG. 3 is an enlarged front view of FIG. 1;

FIG. 4 is an enlarged rear view of FIG. 1;

FIG. 5 is an enlarged top view of FIG. 1;

FIG. 6 is an enlarged bottom view of FIG. 1;

FIG. 7 is an enlarged right side view of FIG. 1; and,

FIG. 8 is an enlarged left side view of FIG. 1.

The broken lines depict environmental subject matter and form no part of the claimed design.

1 Claim, 7 Drawing Sheets
